UNITED STATES PATENT OFFICE.

FRANKLIN B. WEITERSHAUSEN, OF PITTSBURG, PENNSYLVANIA, ASSIGNOR OF ONE-HALF
TO GEORGE G. BLAKELY, OF PITTSBURG, PENNSYLVANIA.

CLOTHES-DRIER.

No. 874,902.

Specification of Letters Patent.

Patented Dec. 24, 1907.

Application filed June 7, 1907. Serial No. 377,797.

To all whom it may concern:

Be it known that I, FRANKLIN B. WEITERSHAUSEN, a citizen of the United States, residing at Pittsburg, in the county of Allegheny and State of Pennsylvania, have invented certain new and useful Improvements in Clothes-Driers, of which the following is a specification.

My invention relates to devices for hanging clothes in the house and has for its object the provision of a device consisting of a clothes frame having a plurality of arms, to receive the clothes, said frame being suspended from the ceiling of the kitchen or laundry by means of jointed frames pivotally secured to the ceiling and clothes frame. Ropes or other flexible elements are secured to the frame and through pulleys on the ceiling to raise and lower the frame and guide strips are secured to the adjacent wall that engage cleats on the rear of the clothes frame.

The construction and advantages of my improved clothes drier will be described in detail hereinafter and illustrated in the accompanying drawings in which—

Figure 1 is a view of a ceiling and side wall showing a side view of my improved clothes drier in its lowest position, Fig. 2, a similar view showing the device in a raised position, Fig. 3, a front view, and Fig. 4, a plan view of the clothes frame.

In the drawings similar reference characters indicate corresponding parts throughout the several views.

35 A indicates the ceiling of a room such as the kitchen or laundry and B the side wall.

1 indicates the clothes frame consisting of a plurality of tapering arms 2 secured at their wider ends 3 to a cross piece 4 and having 40 strengthening pieces 5 secured to arms 2 adjacent to said cross piece 4. The frame 1 is suspended from cleats 6, secured to ceiling A, by means of jointed frames 7 secured at each end thereof. Each of said frames comprises 45 two rods 8 pivotally secured to cleat 6, two other rods 8^a pivotally secured to the end of frame 1 and a cross rod 9, the free ends of

rods 8 and 8^a being pivotally secured to the ends of cross rod 9 as shown at 10.

11 indicates ropes or chains for operating 50 the frame 1 which are secured to strengthening pieces 5 and geared on pulleys 12 secured to the ceiling A.

13 indicates guide strips secured to side wall B and 14 cleats secured to cross piece 55 4 that engage guide strips 13 to prevent lateral movement of the frame 1.

It will be understood that cross rods 9 insure a simultaneous bending of the rods 8 and 8^a at each end of the frame so as to evenly 60 distribute the weight thereon and also to keep the arms 2 horizontal at whatever height the frame may be raised by ropes 11.

9^b indicates the extended end of cross rods 9 that are long enough to prevent the rods 8 65 and 8^a straightening so that they will be bent slightly when the frame is in its lowermost position and collapsing of frame 7 be assured.

Having thus described my invention what I claim is—

1. In a clothes drier, a clothes frame suspended by articulated rods at each end, a cross-rod connecting the joints of said rods at each end of the frame, and means to raise and lower the frame, substantially as shown and described.

2. In a clothes drier, a clothes frame consisting of a plurality of parallel arms secured at one end to a cross-rod, said frame suspended from a suitable support by means of 80 articulated rods, cross rods connecting the joints of said articulated rods, guide strips suitably secured, cleats secured to the cross rod of the frame to engage said guide strips, and means secured to the clothes frame to 85 raise and lower it, substantially as shown and described.

In testimony whereof I hereto affix my signature in the presence of two witnesses.

FRANKLIN B. WEITERSHAUSEN.
